(57) **CLAIM**

The ornamental design for a sleeping bag as shown and described.

DESCRIPTION

FIG. 1 is a front, left and top perspective view of a sleeping bag showing my new design;

FIG. 2 is a rear, right and bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof; and,

FIG. 9 is an enlarged view of a portion labeled as “9” on FIG. 1.

The long dash-short dash broken lines depict enlargement boundaries that form no part of the claim. The evenly broken lines illustrate portions of the sleeping bag that form no part of the claimed design.

1 Claim, 9 Drawing Sheets
